UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed November 26, 1928, Serial No. 321,864. Renewed December 5, 1929.

This invention relates to improvements in car construction.

One object of the invention is to provide means for connecting the body and truck bolsters of the car to prevent separation thereof, especially in the event of collision, including a center pin member of rugged design which may be readily attached to and removed from the bolsters, wherein the pin is of solid construction and of relatively great cross sectional area to provide high resistance against shearing.

Another object of the invention is to provide a solid pin of the character indicated, which may be applied to bolsters which are not readily accessible for insertion of the pin through the top of the body bolster, by applying the pin by insertion upwardly through the truck bolster, the pin being provided with a solid head at the bottom end having shouldered engagement with the truck bolster and having laterally extending lugs at the top which form a head portion having shouldered engagement with the body bolster, the pin-receiving opening of the bolster being provided with slotted walls to permit passage of the lugs while the pin is being assembled with the bolsters, the pin being rotatable to bring the lugs into shouldered engagement with the body bolster and means being provided to lock the pin against rotation with respect to the last named bolster to prevent disengagement of the lugs.

A more specific object of the invention is to provide means for connecting the body and truck bolsters of a railway car, comprising a pin having a head at one end having shouldered engagement with one of the bolsters and provided with two sets of lugs, each set having shouldered engagement with the other bolster, each of said sets of lugs forming a supplementary retaining means for the other, one of said sets of lugs forming a head portion at the end of the pin and the other set being intermediate the ends thereof and engaging the bolster at a point closely adjacent the cooperating bolster.

Other and further objects of the invention

will more clearly appear from the description and claims hereinafter following.

In the drawing, forming a part of this specification, Figure 1 is a top plan view of a portion of the body bolster of a car, illustrating my improvements in connection therewith. Figure 2 is a vertical sectional view through the body and truck bolsters of a car, corresponding substantially to the line 2—2 of Figure 1. Figure 3 is a vertical sectional view at right angles to the view shown in Figure 2 and corresponding to the line 3—3 of Figure 2. And Figure 4 is a horizontal sectional view, corresponding to the line 4—4 of Figure 2.

In said drawings, 10 indicates generally the body bolster of a car, and 11 the truck bolster. The body and truck bolsters may be of any suitable construction and are provided with aligned center pin receiving openings and the usual bearing means.

The truck bolster is provided with the usual pocket or seat 12 which accommodates a bearing block 13 having a concave upper spherical bearing surface 14 which cooperates with a spherical bearing surface 15 formed on the bottom of the body bolster.

In carrying out my invention, I provide the body bolster with a cylindrical pin-receiving portion 16 having top and bottom interior annular flanges 17 and 18 which are interrupted. The interrupted annular flange 17 is disposed a short distance below the top of the body bolster and the full portions of said flange define a substantially circular opening therebetween. Above the flange 17, the pin-receiving opening is of such a size as to accommodate the head of the center pin. Below the flange 17, the opening is expanded, as indicated at 19. The flange 18 is disposed at the bottom of the pin-receiving opening of the body bolster and has the interrupted sections thereof preferably disposed in alignment with the solid or full portions of the upper flange 17. As most clearly illustrated in Figures 1, 2 and 3, the solid portions of each of the annular flanges 17 and 18 are on diametrically opposite sides of the pin-receiving opening. Although, as hereinbefore

stated, the cut-away portions of the flange 18 are preferably disposed in alignment with the solid portions of the flange 17, it will be obvious that the solid portions of the two flanges may be disposed in vertical alignment without departing from the spirit of the invention. The openings between the flanges 17 and 18 are preferably of the same diameter.

10 The pin-receiving opening of the truck bolster 11, which opening is indicated by 20, is preferably of greater diameter than the openings between the flanges 17 and 18, and the aligned opening of the bearing block 13 is made of the same diameter as the opening 20 of the bolster 11. The bolster 11 is also provided with a pocket 21 for receiving the bottom head of the center pin, thus providing an annular shoulder 22 which co-operates with said head.

15 The center pin proper comprises a main body portion which is solid and an annular head 23 at the bottom end thereof which cooperates with the shoulder 22 and is accommodated within the pocket 21 of the bolster 11. The shank portion 24 adjacent the head 23 is of such a diameter as to substantially fit the opening 20 of the bolster 11. At the top end, the pin is provided with 20 a set of laterally projecting diametrically opposite lugs 25—25 which are of such a size as to pass freely through the opening 20 when the pin is being assembled with the bolsters. The flanges 25 are also of such 25 a width that they will pass through the cut-away sections of the interrupted annular flange 17 and when the pin is turned angularly will overlap the solid portions of said flange. The interrupted portions of the flange 18 are also of such an extent that the lugs 25 will freely pass the flange 18 when the pin is in proper position. Intermediate 30 the top and bottom ends, the pin is provided with two additional diametrically opposite, laterally projecting flanges 26—26 which are preferably disposed in a vertical plane at 90° to the plane of the lugs 25.

35 The lugs 26 are also of such a size as to pass freely through the pin-receiving opening 20 of the bolster 11 when the parts are being assembled and will pass the interrupted portions of the flange 18. Immediately below the lugs 25 and immediately below the lugs 26, the pin is formed of such 40 a diameter as to fit the circular openings between the opposed solid portions of each of the flanges 17 and 18.

45 A U-shaped locking member 27 is employed to prevent rotation of the pin with respect to the body bolster when the parts are assembled. The U-shaped locking member 27 fits over the head of the pin, the head being cut away at opposite sides so as to receive the arms of the U-shaped retaining member, and the corresponding sides of the

upper portion of the shank of the pin are flattened, as indicated at 28, to form engaging faces which will fit the inner sides of the arms of the U-shaped member. The arms of the member 27 are of such a width 50 as to fit within the cut-away portions of the flange 17, and, as most clearly shown in Figure 2, extend a considerable distance below said flange. As will be evident, when the locking member is in position with the inner sides of the arms in engagement with the flat opposite side portions of the pin, the pin will be locked against rotation with respect to the body bolster, the arms of the locking member being held in fixed position 55 by the opposed walls of the cut-away portions of the flange 17.

60 In applying my improved center pin to the body and truck bolsters of a car, the pin is inserted through the opening of the truck bolster by first registering the lugs 25 at the upper end of the pin with the cut-away portions of the flange 18, then passing the pin upwardly and turning the same to a position where the lugs 25 will pass the cut-away portions of the flange 17. When the pin is thus positioned, the lugs 26 will also be so positioned as to pass the cut-away portions of the flange 18. When the lugs 25 and 26 have been brought to a position 65 above the flanges 17 and 18, the entire pin is rotated through an angle of 90°, thereby bringing the lugs 25 and 26 in overlapping relation respectively with the solid portions of the flanges 17 and 18. At this time, the 70 flat sides of the pin and the cut-away portions of the head thereof will be in registration with the cut-away portions of the flange 17. The locking member 27 is then applied through the top end of the pin-receiving opening in the body bolster engaging the arms thereof within the openings provided by the cut-away portions of the head of the pin and the cut-away portions of the flange 17. The pin will thus be 75 locked against rotation with respect to the bolster 10, thereby maintaining the lugs 25 and 26 in overlapped relation with the interrupted flanges 17 and 18.

80 As will be evident, the intermediate lugs 26, which cooperate with the flange 18 of the body bolster, supplement the lugs 25 in holding the bolsters assembled, thereby giving additional strength to the pin for holding the bolsters interlocked.

85 By providing the bottom end of the shank of the pin of relatively larger cross sectional area and also by making the portion of the pin which passes through the openings in the body bolster of relatively larger 90 cross sectional area and making the pin of solid construction, the maximum resistance against shearing action is obtained.

95 When it is desired to disconnect the body and truck bolsters, it is merely necessary 95 to

to remove the locking member 27 and rotate the pin to the proper positions to permit the lugs 25 and 26 to pass the interrupted portions of the flanges 17 and 18, the pin being withdrawn through the truck bolster.

5 While I have herein shown and described what I consider the preferred manner of carrying out my invention, the same is merely illustrative and I contemplate all 10 changes and modifications which come within the scope of the claims appended hereto.

I claim:

1. In car construction, the combination 15 with body and truck bolsters having alined center pin openings; of a center pin extending through said openings, having shoul- 20 dered engagement at one end with one of said bolsters to prevent removal of the pin in one direction and having shouldered en- 25 gagement with the other bolster at spaced points to prevent removal of the pin in the opposite direction.

2. In car construction, the combination 25 with body and truck bolsters having alined center pin-receiving openings; of a center pin disposed in said openings, said center pin having a head portion at one end and having shouldered engagement with one of 30 said bolsters; and spaced retaining mem- 35 bers having shouldered engagement with the other bolster, one of said retaining mem- 40 bers being disposed intermediate the ends of the pin.

3. In car construction, the combination 35 with body and truck bolsters having alined center pin receiving openings; of a center pin accommodated within said alined open- 40 ings, said pin having a head portion at one end having shouldered engagement with one of said bolsters; and retaining lugs at the other end having shouldered engagement with the other bolster, and additional re- 45 taining lugs intermediate its ends also having shouldered engagement with the last named bolster.

4. In car construction, the combination 50 with body and truck bolsters having alined pin-receiving openings; of a center pin ex- 55 tending through said openings, said pin having a head portion at one end having shouldered engagement with one of said bolsters and having lugs at the other end having shouldered engagement with the other bolster, said pin also having additional lugs between the ends thereof also having shouldered engagement with said last named bolster, said additional lugs being offset circumferentially of said pin with reference 60 to the first named lugs.

5. In car construction, the combination 65 with body and truck bolsters having alined center pin-receiving openings, one of said bolsters having an outer shoulder and the other bolster having spaced inner and outer

shoulders; of a center pin disposed within said openings, said pin having two spaced sets of lugs engageable respectively with the spaced inner and outer shoulders and a head portion engageable with the other outer shoulder, said spaced inner and outer shoulders having sections thereof cut away to permit passage of the lugs in assembling the pin with the bolster, said pin being axially rotatable to bring the two spaced sets of lugs into overlapping relation with respect to said inner and outer shoulders.

6. In car construction, the combination 70 with body and truck bolsters having alined center pin openings, each bolster being pro- 75 vided with a shoulder adjacent its opening; of a center pin having a head at each end, the shape of one of said heads and the cross section of the opening in one of said bolsters being such that it may be inserted 80 therethrough while in one position, but is prevented from passing therethrough when given a partial turn; lugs on the pin between the ends thereof, having shouldered engage- 85 ment with the last named bolster, and the shank portion of said pin adjacent each head being of a diameter corresponding to the diameter of the pin opening adjacent thereto; and removable means cooperating with the pin to prevent turning thereof relative 90 to one of said bolsters.

7. In car construction, the combination 95 with body and truck bolsters having alined center pin openings, one of said bolsters being provided with a shoulder adjacent the 100 pin opening thereof and the other bolster being provided with a pair of spaced shoul- 105 ders; of a center pin having heads at op- 110 posite ends thereof and retaining lugs be- 115 tween said ends, said lugs being engageable with one shoulder of said pair and one of said heads being engageable with the other shoulder of said pair, and the other head of said pin being engageable with the shoul- 120 der of the other bolster, the cross section of said pin-receiving opening in the bolster having a pair of shoulders and the shape of the head cooperating with said bolster, and the lug of said pin being such as to permit insertion of the pin when the pin is in one angular position and when turned will prevent passage of said head through said bolster opening and also passage of said lug through said opening; and removable lock- 125 ing means preventing turning of the pin with respect to said last named bolster.

8. In car construction, the combination 130 with body and truck bolsters having alined center pin-receiving openings, the opening of one of said bolsters being of larger di- 135 ameter than the opening of the other bolster; of a center pin disposed within said openings, said pin having the shank portions thereof at opposite ends of different diameters to fit said openings; a head at the

end of the pin provided at the shank portion of larger diameter, said head having shouldered engagement with the corresponding bolster; a head at the other end of the pin of a diameter to pass through said opening of larger diameter, said last named head having shouldered engagement with the other bolster, the cross section of the pin opening in said last named bolster and the shape of said last named head being such 10 as to permit insertion when the pin is in one angular position and when turned will prevent passage of said head through the opening of said last named bolster; and removable means for preventing turning of the pin with respect to said last named bolster.

9. In car construction, the combination with body and truck bolsters having alined 20 center pin-receiving openings, the pin-receiving opening of one of said bolsters being of larger diameter than the pin-receiving opening of the other bolster, said bolster having the opening of larger diameter having an annular shoulder adjacent said opening, and the other bolster having interrupted annular shoulders at opposite ends of the opening thereof; of a center pin having the shank thereof of two different diameters to fit said opening of larger diameter 30 and the opening adjacent said interrupted annular shoulders, said pin having a head at one end thereof engageable with said annular shoulder and having two sets of lugs, one set being at the other end of the pin and the other set being intermediate the ends of the pin, said lugs being of a size to pass freely through said opening of larger diameter and to pass said interrupted 40 annular shoulders when alined with the interrupted sections thereof, said lugs of said sets being brought into overlapping relation with the full sections of said interrupted annular shoulders respectively when said 45 pin is turned; and removable means for locking said pin when so turned against rotation with respect to said interrupted annular shoulders.

10. In car construction, the combination 50 with body and truck bolsters having alined center pin openings; of a center pin having a head at one end, a set of lugs at the other end and a second set of lugs spaced inwardly from said last named end, the head 55 of said pin having shouldered engagement with one of said bolsters, and the opening of the other bolster having bayonet slot formations at spaced zones adapted to cooperate with said lugs; and means cooperable with 60 one of said bayonet slot formations for holding the pin against rotation with respect to said last named bolster.

11. In car construction, the combination 65 with body and truck bolsters having alined center pin receiving openings,

each bolster being provided with a shoulder adjacent its opening; of a center pin having heads at opposite ends thereof, one of said heads and the cross section of the openings being such that it may be inserted therethrough while in one position, but is prevented from passing therethrough when given a partial turn; and additional means providing additional shouldered engagement between the pin and one of said bolsters, said additional means being disposed 70 inwardly of the heads of the pin. 75

12. In car construction, the combination with body and truck bolsters having alined 80 center pin receiving openings, each bolster being provided with a shoulder adjacent its opening; of a center pin having a head at each end thereof, the shape of one of said heads and the cross section of the openings being such that the head may be inserted 85 therethrough while in one position, but is prevented from passing therethrough by engagement with the shoulder of the corresponding bolster when given a partial turn; and additional retaining means for said pin spaced inwardly from said last named head 90 and cooperating with the corresponding bolster and having shouldered engagement therewith.

13. In car construction, the combination 95 with body and truck bolsters having alined center pin receiving openings; of a one piece center pin extending through said openings and having head members at opposite ends thereof having shouldered engagement with said bolsters respectively; and additional means on said pin inwardly of the heads thereof also having shouldered engagement with one of said bolsters for preventing removal of the pin. 100

In witness that I claim the foregoing I have hereunto subscribed my name this 20th day of November, 1928.

STACY B. HASELTINE.
